[57] CLAIM

The ornamental design for a dispenser for vaporizable substance, as shown.

DESCRIPTION

FIG. 1 is a perspective view of a dispenser for vaporizable substance showing my new design;

FIG. 2 is a right side elevational view thereof, the left side being a mirror image of the right side shown;

FIG. 3 is a front elevational view thereof;

FIG. 4 is a rear elevational view thereof; and

FIG. 5 is a top plan view thereof.

FIG. 1
